(57) **CLAIM**

I claim the ornamental design for a massage device, as shown and described.

DESCRIPTION

FIG. 1 is an upper perspective view of the massage device; FIG. 2 is a front plan view of the design shown in FIG. 1; FIG. 3 is a rear plan view of the design shown in FIG. 1; FIG. 4 is a left side plan view of the design shown in FIG. 1; FIG. 5 is a right side plan view of the design shown in FIG. 1; FIG. 6 is a top plan view of the design shown in FIG. 1; FIG. 7 is a bottom plan view of the design shown in FIG. 1; and, FIG. 8 is a lower perspective view of the design shown in FIG. 1.

The broken lines shown in the drawings are for the purpose of illustrating portions of the massage device, which form no part of the claimed design. The shade lines shown represent surface shading and not surface ornamentation, color, or material type.
